UNITED STATES PATENT OFFICE.

BENJAMIN A. RUCKER, OF BEDFORD, VIRGINIA.

DOOR LATCH.

Application filed November 28, 1925. Serial No. 71,951.

This invention relates to door latches, and more particularly to a quickly releasable latch for doors of theatres, public buildings, and the like.

5 An object of the invention is to provide a construction in which the release of the latch is controlled by a bar of appreciable length extending across the door at a convenient height to be grasped by the person 10 desiring to open the door.

A further object of the invention is the provision of a device of this character which is of simple construction and which may be readily and easily attached to any door.

15 In the accompanying drawings, I have shown several embodiments of the invention. In this showing:

Figure 1 is a front elevation of the inner side of the door showing one form of the invention applied,

Figure 2 is a plan view of the latch removed from the door,

Figure 3 is a perspective view,

20 Figure 4 is a detail sectional view on line 4-4 of Figure 2,

Figure 5 is an elevation of a portion of a door showing another form of the invention,

Figure 6 is a horizontal sectional view 25 substantially on line 6-6 of Figure 5,

Figure 7 is an elevation of a portion of a door showing another form of the invention, and,

Figure 8 is a horizontal sectional view 30 on line 8-8 of Figure 7.

Referring to Figures 1 to 4 of the drawings, the reference numeral 1 designates a door of ordinary construction and 2 represents a door jamb arranged at the free 40 side of the door. A keeper 3 is mounted on the door jamb and is provided with an opening for the reception of the latch bolt. A plate 4 is adapted to be secured to the door, the plate being provided with suitable openings 5 for the reception of fastening elements. Adjacent the free end of the door, the plate is provided with an upturned end 6 having an opening therein and an ear 7 is arranged intermediate the ends 45 of the plate and provided with an opening in alignment with the opening in the end 6. A latch bolt 8 is arranged in these openings. The latch bolt is provided with the usual beveled end 9. Between the upturned end 6 and the ear 7, the latch bolt is surrounded by a coil spring 10 which is re-

tained in position by means of a pin 11. The bolt is extended to a point beyond the other end of the plate and is connected to the plate by means of a link 12 passing through a sleeve 13 formed on the end of the bolt. The ends of the link are laterally offset, as at 14, and are adapted to be received in curled end portions 15 formed on the plate 4 to hingedly connect the link to the plate.

In the form of the invention shown in Figures 5 and 6 of the drawings, the plate 4 is employed but in connection therewith, I employ a latch bolt 16 of slightly greater 70 length than the distance between the offset end 6 and the ear 7. This bolt is surrounded by a coil spring 17. An operating member 18 is arranged slightly spaced from the plate 4 and is connected to the rear end 75 of the bolt by means of a link 19. The forward end of the operating member is connected to ears formed on the plate 4 by means of a link 20, and the rear end is similarly connected to the plate 4 by means 80 of a link 21.

In the form of the invention shown in Figures 7 and 8 of the drawings, the bolt 16 is pivotally connected to an operating member 22. As shown, the operating member is spaced from the plate 4 in the same manner as in the form shown in Figures 5 and 6 of the drawings and is provided with a curved forward end 23 which is connected to the bolt. The rear end of the operating member is connected to the plate by means of a link 24.

In the operation of the form of the invention shown in Figures 1 to 4 of the drawings, the bolt 8 is normally disposed at an angle to the plate 4 with the bolt projected by means of the spring 10, as shown in dotted lines in Figure 2 of the drawings. When pressure is applied to the bolt to move it from the dotted line position shown in Figure 2 of the drawings, to the full line position, the bolt and link 12 assume the position shown substantially parallel to the plate 4, withdrawing the operating end of the bolt from the keeper and permitting the door to be opened. As shown in Figure 4 of the drawings, the opening in the ear 7 is enlarged sufficiently to permit this angular movement of the bolt.

In the form of the invention shown in Figures 5 and 6 of the drawings, pressure applied to the operating member 18 in

the direction indicated by the arrow causes the links 20 and 21 to swing about the connections to the plate 4 as pivots and the link 19 then exerts a rearward pull on the bolt 5 to retract it against the tension of the spring.

In the form of the invention shown in Figures 7 and 8 of the drawings, the operation is essentially the same and as the operating member 22 moves toward the left and tends to assume a position over the plate 4, the bolt is retracted. In each form of the invention, the spring 10 or 17 is compressed when the latch bolt is retracted and as soon as the pressure is removed from the bolt or operating member, the pressure projects the bolt and causes it to engage the keeper when the door is again closed.

It is to be understood that the forms of my invention herewith shown and described are to be taken as preferred examples of the same, and that various changes in the shape, size, and arrangement of parts may be resorted to without departing from the spirit of the invention or the scope of the subjoined claims.

I claim:

1. A device of the character described comprising a plate adapted to be secured to a closure and extend transversely thereof throughout a portion of its width, a bolt 30 slidably mounted on said plate, means for normally projecting said bolt, a link pivotally connected to the rear end of said plate, and an operating member pivotally connected to said link and connected to said bolt and being adapted to retract said bolt upon the operation thereof in one direction.

2. In a device of the character described, a plate adapted to be secured to a door and extend transversely thereof throughout substantially its entire length, a bolt slidably mounted on said plate, means for projecting said bolt, an operating member arranged substantially parallel to said plate, links 40 connecting the ends of said operating member to the ends of said plate, and a link connected to said operating member intermediate its ends and to said bolt.

In testimony whereof, I affix my signature.

BENJAMIN A. RUCKER.
